METHOD OF TREATING BENIGN
PROSTATIC HYPERSTROPHY

ABSTRACT OF THE DISCLOSURE

Pharmaceutical compositions comprising as the essential active ingredient $1\alpha,2\alpha$ -methylene-6-chloro- 17α -lower alkanoyloxy-6-dehydroprogesterone are useful in the treatment of benign prostatic hypertrophy. Preferred are compositions comprising $1\alpha,2\alpha$ -methylene-6-chloro- 17α -acetoxy-6-dehydroprogesterone.

This invention relates to new therapeutic formulations useful in the control and treatment of benign prostatic hypertrophy and to the process of treating benign prostatic hypertrophy which comprises the administration of dosage units of such therapeutic formulations.

Benign prostatic hypertrophy occurs spontaneously in man as well as dogs. In both species, the frequency of the hypertrophic condition seems to increase with increasing age. In the United States, it has been estimated that more than one-half of the male population over fifty years of age is afflicted with benign prostatic tumors and that the incidence approaches 70 to 90 percent as age increases. Thus benign prostatic hypertrophy presents a major problem for which there has heretofore existed no satisfactory treatment other than surgery.

At the present time, the etiological and pathogenic factors which lead to the hypertrophic condition in dogs and in man are considered by many investigators to be identical. Although numerous theories have been advanced on the etiology of benign prostatic hypertrophy, none have been fully accepted and none have aided in the identification of the true etiology of the problem since the preventive or therapeutic measures heretofore suggested in these theories have failed. For example, most investigators in the field presently believe that benign prostatic hypertrophy results from an imbalance of androgenic and estrogenic hormones, although prostatic growth appears to be androgen-dependent. Hormone therapy (i.e. administration of estrogens such as stilbesterol), however, has not proved to be fully efficacious in providing meaningful remissions and cures, the condition frequently recurring following cessation of estrogen therapy.

Surgical ablation, although an effective therapy for benign prostatic hypertrophy, is not entirely satisfactory since severe complications may arise. In addition to a mortality rate of 2 to 3 percent which may be anticipated in patients subjected to transurethral prostatectomy, many patients experience some nonfatal complications such as epididymitis, pneumonia, pyelonephritis, secondary resection, etc. The need for another and effective form of therapy, therefore, is clear.

The instant invention is based upon applicant's discovery that administration of dosage units of therapeutic formulations containing a 17α -lower alkanoyl ester of

2

$1\alpha,2\alpha$ - methylene - 6 - chloro - 6 - dehydro - 17α - hydroxy-progesterone produces a marked reduction in the hypertrophic prostate. Further, and surprisingly, administration of these esters in dosages sufficient to achieve the anti-hypertrophic response is unaccompanied by objectional side effects, especially the suppression of adrenal function often displayed by progestational hormones. The anti-hypertrophic effect of these compounds has been confirmed by actual *in vivo* evaluation in dogs employing standard pharmacological techniques. Thus, the instant invention constitutes an important advance in the treatment of benign prostatic hypertrophy.

In its composition aspect, therefore, the instant invention is described as residing in the concept of therapeutic formations for the treatment and control of benign prostatic hypertrophy containing as the essential active ingredient $1\alpha,2\alpha$ - methylene - 6 - chloro - 6 - dehydro - 17α - hydroxy-progesterone esterified at the 17-position with a lower alkanoyl acid group.

20 In its process aspect, the instant invention may be described as residing in the concept of the method for the treatment and control of benign prostatic hypertrophy which comprises administering dosage units of a therapeutic formulation containing as the essential active ingredient $1\alpha,2\alpha$ - methylene - 6 - chloro - 6 - dehydro - 17α - hydroxy-progesterone having at the 17-position a lower alkanoyloxy group.

As used herein, the term, "lower alkanoyl acid" is intended to include hydrocarbon carboxylic acids, including 30 straight and branched chain acids, having from 1 to 8 carbon atoms. Included in this group are, for example, but without limiting the generality of the foregoing, acetic acid, propionic acid, butyric acid, 1-methylpropionic acid, valeric acid, hexanoic acid and the like. Acetic acid esters 35 are particularly preferred.

The active esters of this invention are either well-known compounds (see, for example, South Africa Patent 62/1,250, filed Mar. 26, 1962) or may be readily prepared by methods conventional in the art of which the following 40 procedure is typical:

A $1\alpha,2\alpha$ -methylene-6-dehydro- 17α -hydroxy - progesterone 45 17-ester, such as the acetate, is converted into the corresponding $6\alpha,7\alpha$ -epoxide by the action of a percarboxylic acid, such as perbenzoic acid, in a suitable solvent, such as ethylene chloride. The reaction mixture is kept for 12 to 20 hours at about 5° C. and for an additional 5 to 10 hours at about room temperature. It is then diluted, with methylene chloride for example, and washed with aqueous ferrous sulfate solution, sodium bicarbonate solution and with water until neutral. The organic phase is separated and evaporated to dryness. The resulting crude $6\alpha,7\alpha$ -epoxide, preferably in glacial acetic acid, is then saturated with gaseous hydrogen chloride at room temperature for 18 to 24 hours whereby, in one 50 operation, the cyclopropane ring is opened with the formation of a 1α -chloro- 6 -methyl group and the epoxy ring is opened with the splitting off of water and the formation of the 6-chloro-6-dehydro grouping. The crude product, after the reaction mixture has been diluted with methylene chloride, washed neutral with water and dried over sodium sulfate, is recovered by separating the organic phase and evaporating to dryness. The $1\alpha,2\alpha$ -methylene group is then regenerated by refluxing the crude product under a nitrogen atmosphere for about 30 min-

utes with an organic base such as collidine. The reaction mixture is diluted with ether, washed with about 4 N hydrochloric acid, and then washed with water until neutral. The crude residue remaining after drying the reaction mixture over sodium sulphate and evaporating the organic phase to dryness is chromatographed over silica gel preferably with a benzene-ethyl acetate mixture (19:1). Recovery of the eluted product and recrystallization from an organic solvent, such as isopropyl ether, yields the pure $1\alpha,2\alpha$ -methylene-6-chloro-6-dehydro-17 α -hydroxy-progesterone 17-ester (i.e. the acetate in the sequence above).

The active esters of this invention can be administered orally in the form of tablets, capsules, elixirs and the like or may be administered by parenteral injection. In tablet form they are compounded with an inert pharmaceutical carrier which may contain a suitable binder such as, for example, gums, starches, and sugars. They may also be incorporated into gelatin capsules or formulated into elixirs which have the advantage of being susceptible to manipulations in flavor by the addition of standard natural or synthetic flavoring agents. Highly satisfactory administration may also be achieved in the form of aqueous parenteral suspensions. Preferably, these formulations are so proportioned as to afford a unit dosage of from about 1 to about 100 mg. of active ester. Particularly preferred are unit dosages ranging from about 5 to about 25 mg.

Typical formulations incorporating the active esters of this invention are described below. These formulations are intended to be illustrative merely and no limitation is implied or intended except as set forth in the appended claims.

Tablet formulations

Formula A (5 mg.):	Milligrams per tablet
$1\alpha,2\alpha$ -methylene-6-chloro - 6 - dehydro - 17 α -hydroxy-progesterone acetate	5.0
Starch, food grade	5.0
Lactose, USP (spray dried)	89.5
Magnesium stearate, USP	0.5
	100.0

Formula B (25 mg.):	
$1\alpha,2\alpha$ -methylene-6-chloro - 6 - dehydro - 17 α -hydroxy-progesterone propionate	25.0
Starch, food grade	10.0
Lactose, USP (spray dried)	164.0
Magnesium stearate, USP	1.0
	200.0

Pass the steroid through a high speed mill equipped with a 100 to 150 mesh screen. Blend the milled steroid with the starch in a suitable mixing vessel. Add an equal weight of the spray dried lactose to the blend and mix until uniform. Combine the resultant blend with the remainder of the spray dried lactose and mix until uniform. Charge the magnesium stearate with a portion of the active tablet mix and blend. Blend the magnesium stearate mix with the remaining active tablet base. Continue mixing until uniform. Compress to target weight (100.0 mg. for 5 mg. tablet and 200.0 mg. for 25 mg. tablet).

Capsule formulation

Formula:	Milligrams per capsule
$1\alpha,2\alpha$ -methylene-6-chloro - 6 - dehydro - 17 α -hydroxy-progesterone valerate	5.0
Lactose, USP (spray dried)	292.0
Magnesium stearate, USP	3.0
	300.0

Blend ingredients until uniformly mixed. Fill into hard gelatin capsules.

Parenteral suspension

Formula A (5 mg.):	Milligrams per milliliter
$1\alpha,2\alpha$ -methylene-6-chloro - 6 - dehydro - 17 α -hydroxy-progesterone caproate	5.00
Methyl cellulose 15 cps., USP	0.05
Sodium citrate, dihydrate	6.00
Benzyl alcohol, NF	9.00
Methylparaben, USP	1.80
Propylparaben, USP	0.20
Water for injection, USP, q.s. ad	1.00

Formula B (25 mg.):	
$1\alpha,2\alpha$ -methylene-6-chloro - 6 - dehydro - 17 α -hydroxy-progesterone butyrate	25.00
Methyl cellulose 15 cps., USP	0.25
Sodium citrate, dihydrate	30.00
Benzyl alcohol, NF	9.00
Methylparaben, USP	1.80
Propylparaben, USP	0.20
Water for injection, USP, q.s. ad	1.00

Charge 45 l. of water for injection into a suitable stainless steel vessel and heat to 85-90° C. With vigorous agitation, slowly sprinkle the methyl cellulose into the hot water (5 gm. for Formula A or 25 gm. for Formula B). 25 Agitate until the methyl cellulose is thoroughly dispersed and wetted. Add approximately 30 l. of cold (0-5° C.), water for injection. Cool the entire mixture to 8° C. Dissolve the sodium citrate (600 gm. for Formula A or 3000 30 gm. for Formula B) in enough water for injection to make 5 l. of solution. Slowly and with agitation add this solution to the cooled methyl cellulose solution. Dissolve the parabens (180 gm. of methyl and 20 gm. of propyl) in 900 gm. of benzyl alcohol which has been heated to 30° C. Charge this solution to the chilled methyl cellulose 35 solution. Bring the resulting solution to 90 l. with water for injection and agitate until uniform. In a sterile area, pass the batch through a sterile filter. Aseptically transfer about 3.5 l. of the sterile methyl cellulose solution to a 40 separate container reserving the remainder of the batch in a sterile stainless steel mixing tank. Slurry the steroid in a sterile colloid mill with about 2 l. of the separated methyl cellulose solution and add the slurry to the solution in the mixing tank. Rinse the slurry container and the mill with the remaining 1.5 l. of reserved methyl cellulose 45 solution and add the rinse to the mixing tank. Rinse the slurry container and mill with 2 l. of water for injection and add the rinse to the mixing tank. Adjust the volume in the mixing tank to 100 l. with water for injection and agitate until uniform. The batch affords 100 l. of sterile suspension having the proportions of Formula A or Formula B.

In order to achieve a satisfactory response in the treatment and control of benign prostatic hypertrophy, it is 55 usually necessary to administer daily 1 to 4 tablets or capsules as described above. The usual injection dosage is 1 to 4 ml. per day. In severe or aggravated conditions, additional medication may be administered.

Although the invention has been described above in 60 terms of 17 α -lower alkanoyl esters of $1\alpha,2\alpha$ -methylene-6-chloro-6-dehydro-17 α -hydroxy-progesterone as the essential active ingredient, many modifications in these compositions of matter will suggest themselves to one skilled in the art from the foregoing disclosure. It will be obvious, for example, that the chlorine atom at the 6-position may be replaced by other substituents such as a fluoro or a methyl group. It will also be obvious that a lower alkylene group such as methylene may be present at position 16.

The nature of the vehicle employed is not an essential part of this invention. Various modifications in therapeutic formulation will suggest themselves to one skilled in the art.

75 The subject matter which applicant regards as his in-

vention is particularly pointed out and distinctly claimed as follows:

1. The method of treating benign prostatic hypertrophy in an animal having a hypertrophic prostate which comprises the internal administration of dosage units of a therapeutic formulation comprising as the essential active ingredient from about 1 to about 100 mgm. of 1 α ,2 α -methylene-6-chloro-17 α -hydroxy - 6-dehydroprogesterone esterified at the 17-position with a lower alkanoic acid group, whereby said hypertrophic prostate is reduced.

2. The method of claim 1 wherein the lower alkanoic acid group is acetate.

3. The method of claim 1 wherein the lower alkanoic acid group is propionate.

4. The method of claim 1 wherein the lower alkanoic acid group is valerate.

5. The method of claim 1 wherein the lower alkanoic acid group is caproate.
